DEVICE FOR MIXING PLAYING CARDS
OR THE LIKEErich Sachs, Berlin, Germany, assignor to
Eugene A. Roll and Herman T. Lukow, both of
New York, N. Y.Application December 16, 1936, Serial No. 116,113
In Germany October 18, 1934

8 Claims. (Cl. 273—149)

My invention relates to a mixing device, especially to a device for mixing playing cards, game cards or the like.

In order to use the hitherto known devices for mixing playing cards or the like, it is necessary at first to make two equal piles of unmixed cards, which are inserted separately into two sections of the device. The rollers or conveyor bands, which are arranged in the device, remove alternatively one card from each pile and superimpose the displaced cards alternatively in the same sequence upon each other thus producing a third pile, so that the sequence of the "mixed" cards of the third pile easily may be predetermined.

One of the objects of my invention is to provide a device for mixing playing cards or the like, which takes only one pile of unmixed cards and mixes the cards thoroughly, so that the sequence or order of the cards in the pile of mixed cards cannot be known in advance.

Another object of my invention is to provide a mixing device, from which the mixed cards may be taken in a single pile.

A further object of my invention is to provide a mixing device, which may be easily operated and is adapted also to be used by children.

Still another object of my invention is to provide a mixing device, the mixing operation of which cannot be influenced by the operator.

A further object of the invention is to provide a mixing device, in which the cards are advanced with their sides as leading edges so that the entire device has a squat shape.

I accomplish the purposes of my invention by means of a device consisting of a receiving chamber adapted to receive a single pile of unmixed cards and being substantially open at the bottom, two sections arranged at opposite sides of the receiving chamber, collecting means adapted to receive a pile of mixed cards, removing means disposed at the open bottom of said receiving chamber and adapted to displace alternatively at least one card of the pile of unmixed cards from the open bottom of said receiving chamber into either one of said two sections, delivering means to discharge the displaced cards from said sections into said collecting means, and driving means adapted to operate said removing means. In a preferred embodiment of my invention, the width of the receiving chamber is substantially equal to the length of the large sides of the cards, and the removing means displace the cards in a direction vertical to the width of the chamber, so that the cards are advanced with their large sides as leading edges. Furthermore the height

of the space between the lower end of the walls of the receiving chamber and the removing means is substantially equal to the thickness of several superimposed cards, so that the removing means displace several cards at each time and the sequence of the cards in the pile of mixed cards cannot be predetermined.

The above mentioned objects and advantages as well as other objects and advantages will be more fully disclosed in the following specification reference being had to the accompanying drawings forming part of this specification, in which:

Fig. 1 shows a vertical sectional view of a device for mixing playing cards according to my invention.

Fig. 2 is a horizontal sectional view taken on line 2—2 of Fig. 1;

Fig. 3 illustrates a vertical sectional view of another embodiment of a mixing device;

Fig. 4 is a horizontal sectional view taken on line 4—4 of Fig. 3;

Fig. 5 is a top plan view of the collecting drawer of the device as shown in Fig. 3;

Fig. 6 shows a vertical sectional view of still another embodiment of my invention;

Fig. 7 shows a vertical sectional view of another embodiment of my invention whereby the bottoms receiving the piles of mixed cards from the removing rollers are in different levels;

Figs. 8 and 9 illustrate the right hand end of the device according to Fig. 7, indicating two different positions of the collecting means,

Fig. 10 is a horizontal sectional view taken on line 10—10 of Fig. 7, and

Fig. 11 shows a vertical sectional view of a device similar to the device according to Fig. 7, whereby, however, the left hand bottom receiving the pile of unmixed cards from the removing roller is in a higher level than the right hand bottom.

Referring to Figs. 1 and 2, *a* designates the casing of the device, in the upper middle part of which a receiving chamber *b* is arranged which is open at the top or may be closed by a suitable cover (not shown). The chamber *b* has an open bottom, and a cross-bar *d* is arranged below the open bottom. The receiving chamber may be filled with a pile *c* of unmixed cards, which may rest partly on said cross-bar *d* and partly on either one of the rollers *e* or *e'*, which extend into the chamber *b* through the open bottom thereof, so that the spaces *f* and *f'* respectively are formed between said rollers and the lower ends of the walls *h*, *h'* of the receiving chamber. The left hand roller *e* is adapted to be rotated in anticlockwise direction, while the right hand

roller e' is adapted to be rotated in clockwise direction, as indicated by arrows in Fig. 1. Contacting layers g and g' respectively of rough material, such as rubber, are mounted on each of said rollers e and e' respectively and cover about half of the circumference of each of the said rollers. These rollers are arranged in such a way in the device that the contacting layer of one of the rollers (roller e' in Fig. 1) is in the lowest 5 position when the contacting layer of the other roller is in the uppermost position. The side walls h , h' of the receiving chamber b have only such a length that the height of the spaces f , f' between the lower edges of the side walls h , h' 10 and the surface of the contacting layer being in its uppermost position is equal to the thickness of a plurality of superimposed cards, so that the removing rollers e , e' may draw 8-10 cards for example each time out of the receiving chamber b . The width of the chamber b and of the spaces f , f' is substantially equal to the length of the large sides of the cards, so that the latter are advanced in the direction of their short axis. 15

At each side of the receiving chamber and below thereof sections k , k' are arranged, the bottoms l , l' of which are downwardly inclined in the direction to the middle axis of the device and are provided with apertures m , m' through which delivering rollers n , n' of rubber extend. 20 The left hand roller n is adapted to be rotated in clockwise direction, while the right hand roller n' is adapted to be rotated in anti-clockwise direction, as indicated by arrows in Fig. 1. The side walls o and o' of the sections form abutments, against which the piles of cards displaced into said sections bear. The space between the surface of the rollers n , n' and the walls o , o' is sufficient to permit the passage of a single card or 2 cards at the same time. 25

Two partitions p , p' are arranged in the lower part of the casing a and form the collecting chamber q between each other, which is adapted to receive the pile r of mixed cards delivered from the sections k , k' by means of the rollers n , n' . 30 As shown by dotted and dashed lines in Fig. 1, said collecting chamber has an opening through which the pile of mixed cards ready for playing may be removed. The collecting chamber also has a recess indicated by dashed and dotted lines in Fig. 2, to facilitate the removing of the pile of mixed cards. 35

A shaft s provided with a crank handle t is journaled in the casing a and provided with pulleys u and v keyed thereon. 40

The pulley u drives the pulley w keyed on the axle of the roller e by means of a cord. A gear x secured to the other end of the axle of the roller e meshes with a gear x' keyed on the axle of the roller e to rotate the latter in opposite direction to the rotation of the roller e . The pulley v mounted on the free end of the shaft s rotates the rollers n and n' in opposite direction to each other by means of a cord engaged in a suitable manner with the pulleys y and y' keyed on the axles of the rollers n and n' respectively. Thus a single driving shaft s operates the removing rollers e , e' as well as the delivering rollers n , n' but obviously several driving means may be used instead of the single driving shaft s , if desired. Furthermore, a small electro-motor or a motor operated by a spring may be used to rotate the driving shaft s instead of the handle t . 45

The operation of the device is as follows:

75 A pile c of unmixed cards is inserted into the

receiving chamber b , whereupon the driving shaft s is rotated by means of the handle t , so that the removing rollers e , e' are alternatively brought in contact with the lowest card of pile c . Due to the adhesion between the cards of a pile, the roller e or e' draws a plurality of cards at each time out of the receiving chamber b into the section k or k' respectively, whereby the number of cards displaced at each time depends upon the height of the spaces f and f' respectively and upon the adhesiveness existing between the individual cards, so that the number of displaced cards varies within wide limits and cannot be predetermined. The displaced cards form in the section k and k' piles, the lowest cards of which are discharged by the rotating rollers n , n' into the collecting chamber q , whereby due to the size of the apertures m and m' only a single card or not more than two cards pass at the same time into said chamber q to form there a pile r of mixed cards, which may be removed later on after the mixing operation is finished. 5

Referring now to Figs. 3-5 incl., which illustrate another embodiment of the mixing device, it indicates a bottom plate, upon which a casing 2 of any material such as synthetic resin, sheet iron or the like is arranged, the width of which is substantially equal to the length of the cards to be mixed. A receiving chamber 4 is arranged in the upper part of the casing. The outer walls of said chamber 4 are provided with recesses 400 to facilitate the insertion of the pile 5 of unmixed cards. Partitions 3 and $3'$ form the inner walls of said receiving chamber 4 , and a cross-bar 7 is provided at the bottom of the chamber, upon which the pile 5 may rest. The casing 2 is provided with a cover 8 pivoted at 9 to close the receiving chamber 4 , if desired. According to the illustrated embodiment the cover 8 carries a counter-weight 11 , 12 , 13 , the shaft 12 of which is slidable in a guiding collar 10 arranged on said cover 8 . If the cover 8 is in closed position, as shown in Fig. 3, the part 13 of the counter-weight rests upon the uppermost card of the pile 5 and presses it against the removing roller 14 or 15 , 20 which is in operable position. 25

The removing rollers 14 , 15 of rubber or the like are arranged below the receiving chamber 4 , one at each side of the middle axis of said chamber 4 , and are mounted on shafts 140 , 150 supported by two parallel oscillatable plates 16 and 160 . Each of said plates is provided with curved slots 161 and is oscillatably arranged on a shaft 21 mounted in the casing 2 . Pins or stops 163 attached to the casing engage with said slots 161 and serve to limit the oscillations of the cage formed by the members 16 , 160 and the rollers 14 . 30 The front wall of the casing 2 is provided with a hole 162 having a diameter larger than the diameter of a driving shaft 17 , which is provided with a crank handle 18 and passes through said hole. Said driving shaft 17 is journaled in the plates 16 and 160 of the cage, and a pulley 19 keyed on the shaft rotates the removing rollers 14 and 15 in opposite direction to each other by means of a cord 20 , $20'$, as shown in Fig. 3. Said opposite direction of movements of the rollers 14 and 15 is obtained by a simple rotation of the shaft 17 and pulley 19 keyed therewith in clockwise direction, as the portions $20'$ of the cord are in engagement with a second pulley $19'$ (Fig. 4), which is loosely arranged on the shaft 17 and may rotate in opposite direction to the pulley 19 . 35

If the user of the device actuates the crank handle 18 by hand to rotate same, this actuation 40

will cause an additional effect besides the rotation of the rollers 14 and 15. Depending on the position of the crank handle 18, the hand alternatively exerts on the shaft 17 a force directed to the right hand or to the left hand. For example, if the crank handle 18 is in the position shown in Fig. 3, the force exerted on the handle 18 and shaft 17 to rotate same in a clock-wise direction is directed into a left-hand direction, so that the lower part of the cage 16, 160 is moved in a left-hand upward direction and the cage swings about the shaft 21 in clock-wise direction until the left hand roller 15 contacts the lowest card of the pile 5. Then, if the crank handle 18 has been rotated for about 180° and is in a position opposite to the position shown in Fig. 3, the force exerted on the handle 18 and shaft 17 to rotate same further in clock-wise direction is directed into a right-hand direction, so that the lower part of the cage 16, 160 is moved in a right-hand upward direction and the cage swings about the shaft 21 in anti-clock-wise direction, until the right hand roller 14 contacts the lowest card of the pile 5. As the diameter of the hole 162 in the front wall of the casing 2 is larger than the diameter of the shaft 17 passing therethrough, the above mentioned swinging movements of the shaft 17 and the cage 16, 160 can be carried out without any obstruction. Thus, due to the above described oscillatable arrangement of the plates 16, 160, a rotation of the crank handle 18 causes an alternative upwards and downwards movement of the removing rollers 14 and 15 for a short distance, so that the rollers 14 and 15 alternatively contact with the lowest card of the pile 5 during the rotation thereof and draw alternatively the cards into the section 220 or 230 to form in each section the piles 39 and 40. The reciprocating movement of the rollers 14 and 15 also may be produced in another suitable manner, by means of cams or grooved discs for example, and the shaft 17 may be driven by an electro-motor or a motor operated by a spring instead of by means of a handle.

The sections 220 and 230 are disposed at the sides of and somewhat below the receiving chamber 4 and have swingable bottoms 22 and 23 respectively, which may swing about horizontal axles 24 and 25 respectively attached to the casing walls. Counterweights 26 are mounted on the short free ends of the swingable bottoms and serve to return the bottoms into a substantially horizontal position when the cards are slid off from them. The bottoms 22 and 23 are provided with supports 27 and 28 respectively at their other ends, which bear against movable abutments 37 and 38 respectively to be described later on.

The collecting chamber 310 formed by the partitions 32 is arranged in the lower middle part of the device and is provided with a drawer 31 for the reception of the pile 41 of mixed cards. Fig. 5 shows a top plan view of said drawer, which may consist of a simple U-shaped part of sheet iron, which has no side walls, as the partitions 32 prevent the cards from falling out of the chamber 310. The upper parts 34 of the partitions embrace the removing means 14, 15, 16, 160 and are provided with openings 33 through which the piles 39 and 40 may pass into the collecting chamber 310. A rotatable button 36 is mounted on the front wall 35 of the drawer 31 and is connected with a lever 37, the end of which forms the abutment for the support 27 of the swingable bottom 22. A spring (not shown) tends to hold the lever 37 in the position shown in Fig. 3. Preferably,

the lever 37 also locks the drawer 31, which can be removed only after a rotation of the lever. A lug 38 is arranged at the corner of the drawer diagonally opposite to said abutment 37 and forms the abutment for the support 28 of the swingable bottom 23.

The operation of the device illustrated in Figs. 3-5 is as follows.

The cover 8 is raised by gripping the weight 12 with the fingers and brought into the position, as shown with dotted lines in Fig. 3. Then the pile 5 of the cards to be mixed is inserted into the open receiving chamber 4, whereupon the cover 8 is closed and the handle 18 is rotated in clock-wise direction. This rotation of the handle 18 causes a rotation of the removing rollers 14 and 15 in opposite direction to each other and at the same time an alternative upward and downward movement of said removing rollers, whereby cards of the pile 5 are alternatively displaced onto the bottoms 22 and 23 to form at said places the piles 39 and 40. Due to the inevitable inaccuracy of the conveyance by means of the roller mechanism and due to the adhesion between the cards of the pile a different number of cards, i. e. 1-4 cards, is displaced at each time, so that it is impossible to predetermine which one of the cards will be displaced to the left and which one to the right. Furthermore, it is impossible to know, into which one of the swingable bottoms 22 or 23 the lowest card of the pile 5 will be displaced, as it cannot be predetermined which one of the rollers 14 or 15 starts with the displacement.

During the displacement of the cards from the receiving chamber 4 the slidable weight 12, 13 causes a pressure on the pile 5 sufficient to assure a removing of the cards by means of the removing roller 14 or 15 in operable position.

As soon as all of the cards are displaced onto the bottoms 22 and 23 and the piles 39 and 40 are formed, the lever and abutment 37 is moved upwardly by a rotation of the button 36, so that the lever 37 is disengaged from the support 27 and the bottom is tilted downwardly against the stop 122 by the weight of the pile 39, as shown in dotted lines in Fig. 3. Thereby, the pile 39 slides through the opening 33 into the drawer 31. At the moment when the drawer is removed from the collecting chamber 310, the abutment 30 mounted on the drawer is disengaged from the support 28, so that the swingable bottom 23 is tilted against the stop 123 by the weight of the pile 40 and the latter slides through the opening 33 into the drawer 31. After a further movement of the drawer 31 out of the collecting chamber the entire pile 41 of mixed cards may be removed from the drawer. As soon as the swingable bottoms 22 and 23 are free from cards, the counterweights 25 and 26 return the bottoms automatically into their normal horizontal position, so that the device may be operated at once after the reinsertion of the drawer 31.

Fig. 6 shows still another embodiment of the invention. The receiving chamber 43 is again in the upper part of the casing 42 and may be closed by the cover 44 provided with the slidable counter-weight 45. The driving mechanism and the removing roller mechanism are the same as in the embodiment shown in Fig. 3. At each side of the chamber 43 and below thereto are the sections 490 and 530. The device has, however, only one swingable bottom 53, which forms the section 530 and may be rotated about axle 48. The counter-weight 54 secured to the bottom 53

tends to return same into horizontal position. The section 490 has an inclined stationary bottom 49 which leads the cards displaced on it into the drawer 50, when the pile of mixed cards is formed.

The movable abutment for the support of the swingable bottom 53 is formed by a pin 51, which is secured to the front wall 52 of the drawer 50 and extends somewhat into the casing. As soon as 10 all cards are displaced from the receiving chamber 43, the drawer 50 is drawn out of the collecting chamber 500, whereby the abutment 51 is disengaged from the support 55, so that the swingable bottom 53 is tilted and the pile 56 of cards 15 lying on it falls into the drawer 50 on top of the pile of cards resulting from the cards led by the inclined bottom 49 into the drawer, before the drawer 50 is entirely removed from the collecting chamber. The counterweight 54 returns the bottom 20 without any cards thereon into its horizontal position.

Obviously, a removing mechanism as shown in Fig. 1 may be used in the device shown in Fig. 3 instead of the mechanism 16, 160, 14, 15 illustrated in the latter.

It is also possible to provide a device in which both sections are provided with inclined bottoms leading to a collecting chamber in the middle of the device instead of with swingable bottoms. In 30 other words, in such a device the swingable bottoms 22—23 according to Fig. 3 are replaced by the inclined bottoms 49 according to Fig. 6. In such a case, at least one of the two inclined bottoms should be provided with a movable stop, 35 to hold the displaced cards and to permit a temporary assemblance of a pile of cards on the said inclined bottom.

Figs. 7-10 illustrate still another embodiment of my mixing device, which is very simple in its 40 construction. 60 designates the casing, which is provided with the receiving chamber 61. The latter is closed by the cover 62 at its upper part and is open at the bottom. A cross-bar, as indicated by *a* in Fig. 1 for example, is omitted. The pile 63 of unmixed cards is supported by the removing rollers 64 and 65, which are provided with rubber layers 66 and 67 on about half of their circumference. The rollers 64 and 65 may be rotated in opposite direction to each other, as indicated by arrows 68 and 69, by means of a handle 70 through the gears 71 and 72.

The characterizing feature of the embodiment according to Figs. 7-10 consists in the fact that the bottoms 73 and 74 of the sections 75 and 76 respectively, which receive the piles 78, 78' of mixed cards from the removing rollers 64 and 65 respectively, are arranged on different levels. Fig. 7 shows the left hand bottom 73 on a level lower than the level of the bottom 74.

60 The bottom 73 consists of a single plate which is firmly mounted on a pull-rod 77. Said pull-rod is slidably arranged in the middle of the casing and extends through an opening 80 of a movable closing plate 81 at the right hand end of the 65 casing. The projecting end of the pull rod is provided with a button 82. Integral with or firmly attached to the plate 73 is an upright pushing wall 83 the length of which is shorter than the width of the casing. The movable closing 70 plate 81 is attached to the ends of bars 84 and 85 slidably arranged in openings 86 and 87 of the casing wall. Said bars form tracks on which the left hand bottom plate 73 may slide.

The right hand bottom, which lies on an upper 75 level is formed by two plates 74 and 74' (Fig. 10)

attached to the walls of the casing and provided with abutting walls 88 and 88' respectively. The space between said plates 74 and 74' is somewhat larger than the length of the pushing wall 83, so that the latter may be moved between the edges 5 of said plates.

A locking means 89 (Fig. 7) is arranged at the wall of the casing and may be operated by a stop rod 90 (Fig. 10) mounted on the pushing wall 83. If the plate 73 is moved to the right, by means of the pull-rod 77, the stop rod 90 causes an engagement of the pawl 91 of said locking means 89 with the gear 71 as shown by dotted lines, so that the removing rollers are locked. If the plate 73 is returned from its right hand position into its normal left hand position, the locking means 89 is 15 disengaged from the gear 71 by the stop rod 90.

The operation of the device illustrated in Figs. 7-10 is as follows:

If the handle 70 is rotated, the removing rollers 20 64 and 65 draw the cards from the receiving 25 chamber 61 into the sections 75 and 76, as explained above during the description of Fig. 1, so that the piles 78 and 78' are formed in the bottoms 73 and 74 respectively. After the removal of the entire pile 63 from the receiving chamber, the pull-rod 82 is moved to the right, whereby the plate 73 with the pile 78 are displaced from their left hand position through the intermediate position shown by dotted lines in Fig. 7 into a position, where the pushing wall 83 abuts against the edges 92 of the cards placed upon the plates 74 and 74'. During a further movement of the plate 73 to the right the pushing wall 83, which moved between the edges of the plates 74 and 74', pushes 30 the cards of the pile 78' to the right, until their edges 93 abut against the movable closing plate 81. Then, the closing plate 81 is moved together with the plate 73 and the pushing wall 83 to the right and forms with said parts a collecting 35 chamber 94. During the movement from the position shown in Fig. 8 into the end position shown in Fig. 9, and determined by the abutment of the pushing wall 83 against the casing wall, the pile 78' is brought on top of the pile 78, so that the 40 final single pile 95 of mixed cards is formed, which may be removed by hand from the collecting chamber 94 projecting from the casing. During the movement of the plate 73 to the right, the locking means 89 come in engagement with the gear 71, so that the mixing device cannot be 45 operated during the removal of the mixed cards. If the pull-rod 77 is pushed into the casing, the stop rod 90 releases the gear 71 and the mixing 50 device is ready for a new operation.

The device as shown in Fig. 11 is similar to the device according to Figs. 7-10 with the exception of the arrangement of the bottoms of the sections 75 and 76, which receive the cards from the removing rollers 64 and 65. In this embodiment the left hand bottom 730 is in the upper level and consists of two plates spaced from each other and attached to the casing walls, while the right hand bottom 740 consisting of a single plate is in the lower level and forms with the wall 880 attached 60 to it a collecting means 950 inside of the casing. This embodiment has the advantage that the pushing wall 830 passing through the space between the two plates of the bottom 730 moves the pile 780 over the entire length of the bottom 730, 65 whereupon the piles 780 and 780' are combined inside of the casing, i. e. non-visible to the operator, in the collecting chamber 950. After the combination of said two piles to a single pile of mixed cards, the collecting chamber may be 70 75

removed outside of the casing by a further displacement of the pull-rod 770, whereby the pushing wall 830 bears against the wall 880 of the collecting chamber. If the collecting chamber projects from the casing, the single pile of mixed cards may be removed therefrom.

I have shown some preferred embodiments of my invention, but it is clear that numerous changes, combinations, and omissions may be made without departing from the spirit of my invention.

What I claim is:

1. In a device for mixing playing cards or the like, the combination of a casing, a receiving chamber in the upper part of said casing, adapted to receive a pile of unmixed cards and being substantially open at the bottom, two sections arranged at opposite sides of the receiving chamber, two removing means disposed at the bottom 10 of said receiving chamber, one at each side of the middle axis of said receiving chamber, and adapted to displace at least one card of the pile of unmixed cards from the open bottom of said receiving chamber into one of said sections, means 20 to engage alternatively one of said removing means with the lowest card of the pile of unmixed cards, collecting means in the lower part of the casing, delivering means to discharge the displaced cards from said sections into said collecting means to form therein a single pile of mixed cards, and driving means adapted to operate said removing means.

2. In a device for mixing playing cards or the like, the combination of a casing, a receiving chamber in the upper part of the casing adapted to receive a pile of unmixed cards and being substantially open at the bottom, two sections arranged at opposite sides of the receiving chamber, an oscillatable member arranged below the open bottom of said receiving chamber, two removing rollers journaled in said oscillatable member, one at each side of the middle axis of said receiving chamber, said removing rollers being adapted to be rotated in opposite directions 45 and to be engaged with the lowest card of the pile of unmixed cards to displace at least one card of said pile from the open bottom of said receiving chamber into one of said sections, means to oscillate said member to engage alternatively one 50 of said rollers with the lowest card of the pile, collecting means in the lower part of the casing, delivering means to discharge the displaced cards from said sections into said collecting means to form therein a single pile of mixed cards, and 55 driving means adapted to operate said removing means.

3. In a device for mixing playing cards or the like, the combination of a casing, a receiving chamber in the upper part of said casing adapted to receive a pile of unmixed cards and being substantially open at the bottom, two sections arranged at opposite sides of the receiving chamber, removing means disposed at the open bottom of said receiving chamber and adapted to 60 displace alternatively at least one card of the pile of unmixed cards from the open bottom of said receiving chamber into either one of said two sections, each of said sections having at least one plate adapted to receive a pile of displaced cards, 65 said plates being arranged at different levels, delivering means to push the pile of displaced cards from the plate being at the upper level onto the pile being at the lower level to form therewith a single pile of mixed cards, means to move the pile of mixed cards out of the casing, and 70 driving means adapted to rotate said rollers.

75 the pile of mixed cards out of the casing, and

driving means adapted to operate said removing means.

4. In a device for mixing playing cards or the like, the combination of a casing, a receiving chamber in the upper part of said casing adapted to receive a pile of unmixed cards and being substantially open at the bottom, two sections arranged at opposite sides of the receiving chamber, removing means disposed at the open bottom of said receiving chamber and adapted to displace alternatively at least one card of the pile of unmixed cards from the open bottom of said receiving chamber into either one of said two sections, a pull-rod slidably arranged in the lower part of said casing, a plate normally disposed in 15 one of said sections and attached to said pull-rod, said plate being adapted to receive a pile of cards displaced by said removing means, a pushing member secured to said pull-rod, two plates positioned in the other section at a level above 20 the level of the plate attached to the pull-rod, said two plates being adapted to receive a pile of cards displaced by said removing means into said other section and being spaced from each other to form a passage for the pushing member to push 25 the pile of cards resting on said plates onto the pile of cards resting on the plate attached to the pull rod, the casing having an opening in the side thereof, a movable closing plate arranged on said opening, said plate attached to the pull rod being 30 adapted to be moved against said movable closing plate to form therewith collecting means for a single pile of mixed cards and to be moved together with said movable closing plate out of the casing, and driving means adapted to operate 35 said removing means.

5. In a device as claimed in claim 3, locking means adapted to lock said driving means, and actuating means mounted on said movable pushing means and adapted to actuate said locking 40 means.

6. In a device for mixing playing cards or the like, the combination of a casing, a receiving chamber in the upper part of the casing adapted to receive a pile of unmixed cards and being substantially open at the bottom, two sections arranged at opposite sides of the receiving chamber, two removing rollers disposed at the open bottom of said receiving chamber, one at each side of the middle axis of said receiving chamber, contacting 45 layers mounted on the surface of each of said removing rollers, each of said layers covering about half of the circumference of the roller, whereby the rollers are arranged in such a way that the contacting layer of one of the rollers is in 50 the lowest position, when the contacting layer of the other roller is in the uppermost position, said rollers being adapted to displace alternatively at least one card of the pile of unmixed cards from the open bottom of said receiving chamber into 55 one of said sections, each of said sections having at least one plate adapted to receive a pile of displaced cards, said plates being arranged at different levels, delivering means to push the pile of displaced cards from the plate being at the upper 60 level onto the pile being at the lower level to form therewith a single pile of mixed cards, means to move the pile of mixed cards out of the casing, and driving means adapted to rotate said rollers. 65

7. In a device for mixing playing cards or the like, the combination of a casing, a receiving chamber in the upper part of the casing adapted to receive a pile of unmixed cards and being substantially open at the bottom, two sections arranged at opposite sides of the receiving chamber, 70

an oscillatable member arranged below the open bottom of said receiving chamber, two removing rollers journaled in said oscillatable member, one at each side of the middle axis of said receiving chamber, said removing rollers being adapted to be rotated in opposite directions and to be engaged with the lowest card of the pile of unmixed cards to displace at least one card of said pile from the open bottom of said receiving chamber into one of said sections, means to oscillate said member to engage alternatively one of said rollers with the lowest card of the pile, each of said sections having at least one plate adapted to receive a pile of displaced cards, said plates being arranged at different levels, delivering means to push the pile of displaced cards from the plate being at the upper level onto the pile being at the lower level to form therewith a single pile of mixed cards, means to move the pile of mixed cards out of the casing, and driving means adapted to operate said removing means.

8. In a device for mixing playing cards or the like, the combination of a casing, a receiving chamber in the upper part of the casing adapted to receive a pile of unmixed cards and being sub-

stantially open at the bottom, two sections arranged at opposite sides of the receiving chamber, removing means disposed at the open bottom of said receiving chamber and adapted to displace alternatively at least one card of the pile of unmixed cards from the open bottom of said receiving chamber into either one of said two sections, two plates arranged in one of said sections and adapted to receive a pile of displaced cards, said two plates being spaced from each other, a plate slidably arranged in the other section at a level below the level of said two plates and adapted to receive another pile of displaced cards, said plate being provided with walls to form a collecting casing, a pull-rod slidably arranged in the lower part of the casing and provided with a pushing wall passing through the space between said two plates arranged at the higher level, said pushing wall being adapted to push the pile of cards resting on said two plates onto the pile of cards resting on the plate arranged at the lower level and to move said collecting casing out of the device, and driving means adapted to operate said removing means.

ERICH SACHS. 25
